UNITED STATES PATENT OFFICE.

ARTHUR P. CURTIS, OF FITCHBURG, MASSACHUSETTS, ASSIGNOR TO IVER JOHNSON'S ARMS & CYCLE WORKS, OF FITCHBURG, MASSACHUSETTS, A CORPORATION OF MASSACHUSETTS.

SAFETY MECHANISM FOR BOLT-ACTION RIFLES.

Application filed April 22, 1927. Serial No. 185,846.

My invention relates to a safety mechanism for bolt action rifles and has for its object to provide a mechanism that will be automatically set by the closing of the rifle bolt after loading to prevent the rifle from being discharged until the user has manually operated the safety device from its safety position to a firing position.

In bolt action rifles as heretofore constructed it has usually been necessary to manually cock such rifles when the bolt is closed after reloading, for should such rifles be automatically cocked by the mere action of closing the bolt, there would be very serious danger of accidental discharge due to the hammer revolving on a stationary sear, premature operation of the trigger mechanism, or release of the hammer by a hand blow or shock.

According to the present invention I provide a bolt action rifle in which the act of closing the bolt actually leaves the hammer to its cocked position, while, at the same time my safety device prevents the cocked hammer from being released by operation of the trigger and its associated sear. In other words, my improved safety mechanism automatically disconnects the hammer from the trigger mechanism so that it is impossible to discharge the rifle by pulling the trigger until after the user has manually operated the safety device and thereby rendered the hammer capable of being operated by release of the trigger operated sear. With my improved mechanism in its safe position, a blow or hard knock on the fire arm has no effect and cannot cause premature discharge of the cartridge, all as will hereinafter more fully appear, reference being had to the accompanying drawings in which—

Fig. 1 is a view in side elevation of a portion of a bolt action rifle embodying my invention.

Fig. 2 is a longitudinal sectional view showing the position of the parts following the discharge of the rifle.

Fig. 3 is a view similar to Fig. 2 showing the position of the parts following the loading of the rifle and the closing of the bolt, my mechanism then being "on safety".

Fig. 4 is a fragmentary view similar to Fig. 3, showing the position of the parts after the safety device has been operated to

release the hammer to the "firing position".

Like reference characters refer to like parts in the different figures.

Referring to Fig. 1, the rifle generally comprises a barrel 1 mounted on a suitable stock 2, the end of the barrel 1 carrying a bolt sleeve 3, within which operates a slide bolt 4. The bolt 4 is provided with a suitable handle 5 which when in a horizontal position coacts with the sleeve 3 to lock the bolt 4, whereas when the handle 5 is turned upwardly, as shown in dotted lines, the bolt 4 may be moved rearwardly to open the chamber and eject the discharged cartridge shell 6 in the usual manner.

The bolt 4 is provided with a central longitudinal opening 7 within which is slidably mounted a firing plunger 8, the end of the plunger 8 providing a firing pin 9 adapted to be projected through a hole 10 in the end of the bolt 4 to engage the rim of the shell 6, as shown in Fig. 2. The other end of the opening 7 in the bolt 4 is partially closed by a bushing 11 which closely engages the plunger 8, and a spring 12 is confined between the bushing 11 and a shoulder 13 on the firing plunger 8. A set screw 14 extends through the bushing 11 to engage a slot 15 provided in the plunger 8 and thus maintain the firing pin 9 in alignment with the hole 10.

The plunger 8 extends beyond the bolt 4 and is connected at its outer end to a hammer 16 by means of a pin 17. The hammer 16 is also slideable in the bolt sleeve 3 and is provided with a slot 18 at its outer end, within which is pivotally mounted a safety lever 19, the walls of the slot 18 providing a bearing for the pivot pin 20 of the lever 19. The hammer 16 also provides a central opening 21 in which is confined a hollow plunger 22 which is urged in the direction of the safety lever 19 by means of a small spring 23.

When the bolt 4 is unlocked by its handle 5 and withdrawn from the position shown in Fig. 2, it carries with it the firing plunger 8 and the hammer 16, and as the outward movement of the hammer 16 causes the end portion 24 of the safety lever 19 to clear the end of the sleeve 3, the spring 23 acting through plunger 22 turns the lever 19 about its pivot 20 into the position shown in Fig. 3. Therefore, when the bolt 4 is closed by,

its handle 5, after reloading the rifle, the return movement of the hammer 16 with the bolt 4 is arrested by the engagement of the lever portion 24 with the end of the sleeve 3. This also arrests the movement of the firing plunger 8, so that when the bolt is completely closed, the spring 12 is considerably compressed between the bushing 11 and the shoulder 13 on the firing plunger, and the firing pin 9 itself is maintained withdrawn from the opening 10.

As shown in Fig. 3, the arrestation of the movement of the lever 19 when the bolt 4 is closed, prevents the inner end of the hammer 16 from engaging the sear 25 that is connected to the trigger 26 in the usual manner, so that pulling of the trigger 26 will depress the sear 25. So long as the hammer 16 is held in this position it is obvious that pulling the trigger 26 to depress the sear 25 will have absolutely no result in so far as releasing the hammer 16; and consequently, there is no way in which the rifle can be discharged so long as the lever 19 remains in its safe position, as shown in Fig. 3.

When, however, it is desired to discharge the rifle it is only necessary for the user to depress the lever 19 as by means of the thumb, thereby turning the lever about its pivot 20 and freeing the end portion 24 from the end of the sleeve 3. When this occurs the compressed spring 12, acting through the plunger 8, draws the hammer 16 inwardly until the inner end of the hammer 16 engages the upwardly extending sear 25. At this time, the end 24 of the safety lever 19 moves inside the end of the sleeve 3 and the lever 19 can be no longer turned. The position which the parts occupy following the depression of the lever 19 is illustrated in Fig. 4, which represents the "firing" position of the mechanism.

With the parts in the firing position, pulling the trigger 26 will depress the sear 25, and release the hammer 16 therefrom, whereupon the spring 12 acts upon the firing plunger 8 to forcibly impel the firing pin 9 through the opening 10, thereby discharging the cartridge 6, as shown in Fig. 2. When the bolt 4 is withdrawn to eject the discharged cartridge and is closed again after reloading the rifle, the safety lever 19 will again be turned about its pivotal axis to the position shown in Fig. 3, and the hammer 16 will again be withheld from engagement with the hammer sear 25 until released by operation of the safety lever 19.

From the foregoing then it is apparent that by my invention I have provided an improved safety mechanism for bolt action rifles by the use of which it is possible to prevent the rifle from being accidentally discharged. With my invention it is necessary for the user to manually depress the safety lever 19 before it is possible to dis-

charge the rifle by pulling the trigger 26, although this depression of the lever 19 can be readily accomplished by the thumb as the rifle is brought to the shoulder for aiming. If the user attempts to aim the rifle before depressing the safety lever 19, it is apparent from a consideration of Fig. 1, that the end of the safety lever 19 will project into the line of sight so that the attention of the user will be called to the fact that the safety lever has not been depressed and that the rifle cannot be fired.

I claim,

1. A safety mechanism for a bolt action fire arm, comprising a bolt actuated safety member movable automatically to prevent discharge of the fire arm until after said member has been manually moved from its safe position to its firing position.

2. A safety mechanism for a bolt action fire arm, including in combination a bolt and a safety member automatically positioned by operation of the bolt so as to prevent discharge of the fire arm until said safety member has been manually moved from its locked safe position to an unlocked firing position.

3. A safety mechanism for a bolt action fire arm, including in combination a bolt and a safety member movable to automatically assume a safe position upon drawing back and returning the bolt, said safety member in its safe position preventing the fire arm from being discharged.

4. A safety mechanism for a bolt action fire arm, including in combination a bolt and a safety member movable to automatically assume a safe position upon drawing back and returning the bolt, said safety member preventing the discharge of the fire arm until it has been manually moved from a safe position to a firing position.

5. A safety mechanism for a bolt action fire arm, including in combination a bolt and a safety member movable to automatically assume a safe position upon operation of the bolt, said member in its safe position being so disposed as to interfere with a free view of the sights of the fire arm.

6. A safety mechanism for a bolt action fire arm, including in combination a bolt and a safety member movable to automatically assume a safe position upon operation of the bolt, said safety member being disposed to prevent a clear view of the sights when in a safe position, and adapted to be manually moved out of line with the sights to a firing position.

7. A safety mechanism for a fire arm having a bolt action, comprising in combination, a bolt, a hammer operable by the bolt, and a safety member pivotally connected to said hammer and movable to prevent a complete return of said hammer when the bolt is moved to its locked position.

8. In a fire arm, the combination with a longitudinally movable bolt having a firing plunger movable therewith, and a hammer connected to said firing plunger, of a safety member carried by said hammer adapted to automatically assume a safe position when said bolt is moved outwardly preparatory to loading said fire arm.
9. In a fire arm, the combination with a longitudinally movable bolt having a firing plunger movable therewith, and a hammer connected to said firing plunger, of a safety member carried by said hammer adapted to automatically prevent the full movement of said hammer to a firing position when said bolt is moved to close the chamber.
10. In a fire arm, the combination with a longitudinally movable bolt having a firing plunger movable therewith, and a hammer connected to said firing plunger, of a locking member adapted to be automatically moved to a safe position by the withdrawal of the bolt, in which position said member prevents the full movement of said hammer to a firing position upon closing said bolt.
11. In a fire arm, the combination with a longitudinally movable bolt, a hammer operable by said bolt, and a trigger actuated sear adapted to be engaged by said hammer when said bolt is closed, of a safety member carried by said hammer adapted to automatically prevent said hammer from engaging said sear upon initially closing said bolt.
12. In a fire arm, the combination with a longitudinally movable bolt, a hammer operable by said bolt, and a trigger actuated sear adapted to be engaged by said hammer when said bolt is closed, of a safety member carried by said hammer and adapted to prevent the engagement of said hammer with the trigger sear until after said safety member has been manually moved to a firing position.
13. In a fire arm, the combination with a longitudinally movable bolt, a hammer operable by said bolt, and a trigger actuated sear adapted to be engaged by said hammer after said bolt is closed, of a safety member carried by said hammer and adapted to be automatically moved to a position in which it prevents engagement between said hammer and said sear when said bolt is withdrawn for loading the fire arm.
14. In a fire arm, a longitudinally movable bolt having a hammer movable therewith, said hammer carrying a safety lever pivotally connected to one end thereof, turnable to prevent the full return of said hammer when said bolt is closed.

Dated April 6, 1927.

ARTHUR P. CURTIS.
